UNITED STATES PATENT OFFICE.

FREDRICK A. SWAN AND CHARLES B. BOSWORTH, OF BOSTON, MASS.

CUT-OUT FOR DANGEROUS ELECTRIC CURRENTS.

SPECIFICATION forming part of Letters Patent No. 274,150, dated March 20, 1883.

Application filed July 1, 1882. (No model.)

To all whom it may concern:

Be it known that we, FREDRICK A. SWAN and CHARLES B. BOSWORTH, both of Boston, in the county of Suffolk and State of Massachusetts, have invented a new and useful Improved Cut-Out for Dangerous Electric Currents, of which the following is a specification.

Our invention relates to that class of cut-outs in which it is desirable to cut out the wires of a single light, and not to interfere with the current on the main line, the object being to place the operating device within easy reach, and yet to have no currents in any easily accessible position, so that there need be no dangerous electrical currents in any place likely to be occupied inadvertently. This object we attain by the mechanism illustrated in the accompanying drawings, in which—

Figure 1 is a diagram illustrating our devices, and Fig. 2 shows the same in part, the movable part of the cut-out being represented in the position which it occupies when the light and its wires are cut out of circuit.

B represents an electric light of ordinary construction supplied with circuit-wires B' B³, which connect with the binding-posts B B².

The wires L and L² are the line-wires, which connect with the binding-posts L' L³, one of which is connected by a spring-plate, S', to an insulated bed-plate, C, while the other, L³, is connected by a spring-plate, S, to the insulated bed-plate C'. The bed-plates C and C' are shaped as shown, and attached to a block, E, which slides in the bed-piece A. The block E is held in position by the hook-pawl H, which engages with the projection E'. The spring F is at tension, one end being fast to the sliding block E, while the other is fixed to the bed-piece A, so that the tendency is to cause the block E to slide in the direction of the arrow R when released from the hook-pawl H.

The motion of the hook-pawl H is controlled by the electro-magnet M, acting through the armature H', the electro-magnet M being charged by the wire D (connected to the light-wire B³) and the wire D', contact-breaker D⁶ D⁵ D⁴ D³, and wire D², (connected to the light-wire B').

When the contact-breaker is open, as shown in the drawings, the current passes to the light and does not affect the magnet M; but if the contact at D⁵ D⁶ is made the magnet M acts and withdraws the hook-pawl H, thus releasing the block C' and allowing it to be drawn by the spring F, so as to occupy the position shown in Fig. 2.

The operation of our device is as follows: When it is desirable to have the light and its wires B' and B³ in circuit, the cut-out device is in position shown in Fig. 1, in which case the current passes from the line-wire L², through post L³, spring-plate S, bed-plate C', spring-plate S², post B, and wire B', to light; then, through wire B³, post B², spring-plate S³, bed-plate C, spring-plate S', and post L', to line-wire L.

To cut out the light and its wires B' B³ it is necessary to close the contact in the breaker at D⁵ D⁶. This action will cause the magnet M to act and withdraw the hook-pawl H, thus releasing the sliding block E and allowing it to assume the position shown in Fig. 2, in which case the spring-plates S² S³ and light-wires B' B³ are disconnected, while the spring-plates S S' are connected and the line-circuit is complete.

The cut-out device C C' should be put in such a place as to insure it and the connecting line and light wires from being liable to be touched inadvertently; but the contact-breaker may be placed in any convenient place easily accessible to any person who may want to cut out the light and its wires.

We claim—

In an electric-circuit cut-out device, the combination of the light-wires B' B³ and the cut-off wires D² D D' with the cut-out mechanism (consisting of the electro-magnet M, catch H, switch-block E, and spring F) and circuit-breaker, all operating together substantially as described, and for the purpose set forth.

FREDRICK A. SWAN.
CHARLES B. BOSWORTH.
